UNITED STATES PATENT OFFICE.

GEORGE K. SCHAUER, OF OSBORN, OHIO, ASSIGNOR TO HIMSELF AND
CHRISTIAN A. HERR, OF SAME PLACE.

CROCK-CARRIER.

SPECIFICATION forming part of Letters Patent No. 357,339, dated February 8, 1887.

Application filed November 23, 1886. Serial No. 219,691. (No model.)

To all whom it may concern:

Be it known that I, GEORGE K. SCHAUER, of Osborn, in the county of Greene and State of Ohio, have invented a new and Improved 5 Crock-Carrier, of which the following is a specification, reference being had to the annexed drawings, forming a part thereof, in which—

Figure 1 is a side elevation of my improved crock-carrier. Fig. 2 is a vertical transverse 10 section taken on line $x-x$ in Fig. 1. Fig. 3 is a transverse section taken on line $y-y$ in Fig. 1, and Fig. 4 is a transverse section taken on line $z-z$ in Fig. 3.

Similar letters of reference indicate corresponding parts in all the views.

The object of my invention is to provide a simple and effective device whereby two crocks may be simultaneously grasped and carried.

My invention consists of a pair of levers 20 crossed and pivoted together and provided with angled serrated jaws, the longer arms of the levers being bent inwardly toward each other and apertured for receiving an elastic bail, by means of which the jaws are drawn 25 together as the crocks are lifted.

It also consists in the combination, with the jaws thus pivoted together, of a leather tongue suspended from the levers and adapted to engage the rims of the crocks, all as hereinafter 30 more fully described.

The levers $A A'$ are crossed and pivoted upon the straight part of the loop B . The shorter arms $a a'$ of the levers $A A'$ are provided with angled jaws $b b'$ having their inward faces serrated. The loop B is bent down upon opposite sides of the levers $A A'$, and its lower portion is widened to receive the leather tongue C , consisting of a strip of leather bent around the wire of the loop and fastened together below the loop by rivets c .

The longer arms of the levers $A A'$ are curved inward toward each other and apertured near their ends to receive a wire bail, D , the hooks

d of the bail being inserted in the apertures of the levers and bent over toward the body of 45 the bail. The middle part of the bail is made straight, and the wooden handle E is placed thereon for convenience in operating the carrier and lifting the load grasped by the carrier. Normally, the longer arms of the levers 50 $A A'$ are spread by the elasticity of the bail D , thus throwing the jaws $b b'$ open to receive a pair of crocks.

When the carrier has only its own weight to support, the jaws $b b'$ remain apart, and when 55 the rims of a pair of crocks are placed upon opposite sides of the tongue C , with the rims projecting over the rounded upper part of the tongue, as shown in Fig. 1, a slight upward pull upon the bail D closes the jaws $b b'$ together upon the inner surfaces of the crocks, thereby bringing the sides of the crocks below the rims and the rims of the crocks into engagement with the tongue C , when the crocks 60 may be lifted, securely held, and carried. 65

Having thus fully described my invention, I claim as new and desire to secure by Letters Patent—

1. In a crock-carrier, the combination of the levers $A A'$, the angled jaws $b b'$, formed on or 70 attached to the shorter arms of the levers, the tongue C , suspended from the levers, and the bail D , connected with the longer arms of the levers, substantially as described.

2. The combination of the levers $A A'$, having inwardly-bent ends and provided on their shorter arms with serrated jaws $b b'$, the loop B , forming the pivot of the levers $A A'$, the tongue C , received on the loop, and the bail D , connecting the free ends of the longer arms of 80 the levers and provided with the wooden handle E , substantially as described. 75

GEORGE K. SCHAUER.
